SHAVER AND HAIR RECEIVING
COMPARTMENT THEREFORIvar Jepson, Oak Park, Ill., assignor to Sunbeam
Corporation, Chicago, Ill., a corporation of Illi-
nois

Application October 29, 1947, Serial No. 782,761

6 Claims. (Cl. 30—41)

1

This invention relates to shaver and hair receiving compartment therefor.

In electric shavers of the type using a linkage for changing the rotational motion of a motor shaft to an oscillatory movement in a cutter blade, the respective parts forming the linkage are under tremendous strains. In instances where the motor speed may be in excess of 8000 revolutions per minute, pressures in excess of a pound and a half on the respective parts of the linkage are encountered. Such pressures together with friction, wear, and heat incident thereto, cause an early fatiguing of the metal parts. Accordingly, it is an object of this invention to provide a novel drive mechanism that insures a relatively long life under the extreme conditions outlined above.

Another object of the invention is to provide a shaver of the type described characterized by a comb having a shaving area substantially larger than was heretofore practicable, combined with a cutter oscillating across such larger area. This materially increases the difficulties incident to the operating conditions described, and my invention aims to provide an improved shaver head and drive mechanism for such conditions.

Another object of the invention is the provision in a razor of the above character having a linkage with a shaft with novel means for minimizing the axial bodily movement of the shaft.

Another object of the invention is the provision in an electric razor of the above character of novel means for securing a comb in position at one end of the razor.

Another object of the invention is the provision in an electric razor of novel means for receiving hair clippings and the like.

A still further object of the invention is the provision of an electric razor in which the component parts can be easily assembled, which are rugged, and which are relatively inexpensive to manufacture.

Other objects and advantages of the invention will become apparent from the following detailed description taken in connection with the accompanying drawings, in which—

Figure 1 is a side elevational view having a cutaway portion of an electric razor embodying my present invention;

Figure 2 is an end elevational view with a cutaway portion of an electric razor embodying my invention;

Figure 3 is a side elevational view with a cutaway portion showing the construction of the head end of the razor;

Figure 4 is an end view similar to Figure 3;

2

Figure 5 is an elevational view of the head end of the razor with some of the parts removed;

Figure 6 is a fragmentary sectional view similar to Figure 4 showing the parts in a different position;

Figure 7 is a sectional view showing details of construction of the power terminal end of the razor;

Figure 8 is an end view similar to Figure 7;

10 Figure 9 is an exploded view showing one of the parts forming the head and the drive mechanism;

Figure 10 is a diagram showing the present comb in comparison with the prior comb; and

15 Figure 11 is a top view of a spring member which coacts with the comb locking plates, as viewed on the section line 11—11 of Figure 3.

Referring now to the drawings, the invention is shown embodied in an electric razor 11 of the 20 type used in shaving beards and for removing hair from other parts of the body. The razor comprises a cutter 12 coating with a comb 13 secured to comb supports 14 mounted on a head 15 at one end of the razor 11. The cutter 12 is

25 positioned so that it is urged outwardly into constant engagement with the comb 13 by centrifugal force combined with spring force. This principle is disclosed in Patent No. 2,081,694. According to the present invention the spring force is applied by means of a spring 17 mounted in 30 each spaced support 18. The latter are rigidly mounted to a shaft 19 journaled by bearings 21 received in openings 22 in side portions 23 of the head 15. Herein the shaft 19 is driven by a rotatable eccentric 24 through a drive bracket 26.

35 The eccentric 24 and bracket 26 are arranged to translate rotational motion of the eccentric 24 to an oscillatory motion in the shaft 19 and the cutter 12. The eccentric 24 herein is driven by an electric motor 27 mounted in a case 28 preferably shaped to be conveniently grasped in the 40 user's hand.

One phase of the invention is directed to the problems incident to the relatively large comb which is provided with a shaving area substantially larger than in prior shavers of this type.

45 As shown in Figure 10, the arc A shows the outside diameter of a comb according to the present invention, on the same scale as the drawings; and the arc B is the outside diameter of a prior comb. In actual practice the comb plates are of .002" sheet steel and the radius of comb A from its cutting surface to the center is $\frac{1}{2}$ ", while the similar radius for the comb B is $\frac{5}{16}$ ". Assuming the angular movement of the cutter is 50 the same in both cases as denoted by the angle

C, the cutter has much greater lineal travel in the arc A than in the arc B; also, the larger radius would require greater mass of the oscillating parts. In view of the increased mass and the high speeds, very high inertia forces are produced in addition to the increased centrifugal force, and this presents conditions and problems working against the desired long life in a device of this kind. For example, where the size of an oscillating part such as the shaft 19 is increased, the moment of inertia is increased in proportion to the 5th power, meaning that where the shaft is twice the size of a prior construction the inertia forces built up in the shaft are 32 times as large. And, since the bearing pressure on the crank drive pin or eccentric 24 is proportional to the amount of inertia of the oscillating parts, this pressure will also be increased 32 times. Also, further problems are presented because with increased radius of the cutter the centrifugal force working outwardly against the comb is increased in proportion to the radius. These conditions present difficult problems of friction, wear, and fatigue of metals, which affect the life of a device of this kind. My invention has, therefore, provided novel construction designed to meet these problems in a commercially satisfactory manner.

The present invention provides a cutter and its support of substantially reduced mass, considering the large radius and travel. The supports 18, integral with the shaft 19 and originally solid metal, are bored out from the bottom as shown in Figure 3, the bore terminating short of the end. Each support is then milled transversely in a manner to provide a short opening 20 at the outer side and a long opening 20' at the inner side, as shown in Figures 3 and 9. The cutter 12, reduced to minimum dimensions is mounted for sliding support in the slotted ends of the supports 18. As a means of providing sufficient bearing for the cutter in the supports I have provided narrow legs 30 which slide in the slots. The lower end of each leg is reduced to a small size sufficient to enter the small bore in the corresponding support. This lower end of each leg bears against a small disc 30' which seats on the top of each spring 11. Each spring is retained at its lower end by swaging the open end of the bore as shown in Figure 3. The legs 30 provide increased bearing surface for the cutter. Also, the outer edge of each leg has lateral bearing support at all times against the wall of the bore and the inner side of each leg is free to move lengthwise in the longer slot 20' at the inner side of the support. In this way the cutter is guided against lateral displacement and it is free to move in a radial direction in response to centrifugal force and also in response to the springs. This construction contributes to minimum mass of the oscillating parts.

Also directed to this phase of the invention is the construction of the drive bracket 26 so that the latter will have a relatively long life under the extreme service conditions encountered in an electric shaver in which the moving parts thereof reverse their direction of movement many thousands of times a minute. For this purpose the drive bracket 26 comprises a portion 29 (see Figure 9) having an elongated slot 31 shaped to receive the eccentric 24 and a resilient portion 32 for connecting the slot portion 31 to the shaft 19. As best shown in Figures 3, 4 and 9 the slot portion 31 of the bracket is formed herein by spaced elongated members 33 joined together at opposite ends by integral members

34. To minimize friction between the side walls of the slot 31 and the eccentric 24 the walls of the slot are lined with strips 36 of material preferably providing a good bearing surface and also having good insulating qualities so as to insulate the eccentric 24 from the cutter 12. The resilient portion 32 herein is formed by spaced arms 37 integral respectively with a central portion of one of the spaced elongated members 33. Preferably the arms 37 are rigidly secured to a central portion of the shaft 19 as by rivets 38. To increase the resiliency of the respective arms 37 apertures 39 are formed therein intermediate the rivets 38 and the interconnection with the spaced elongated members 33. It is to be understood that with the construction of the drive bracket 26 shown herein it can be formed as a single stamping from resilient material and then preshaped to the desired form in a simple forming process. It is also to be understood that because of the resiliency the shock load on the eccentric 24 at the end of each stroke is minimized.

Preferably the eccentric 24 and the drive bracket 26 are operable to drive the cutter 12 without being exposed to hair clippings falling in the cutter chamber 41 (see Figures 3 and 4). To this end the eccentric 24 and the lower portion of the drive bracket 26 as shown in the respective drawings are disposed in a chamber 42 in the head 15 below the shaft 19. Herein the chamber 42 is formed by the side portions 23 and walls 43 integral with the respective side portions 23. The resilient portion 32 of the drive bracket connected to the shaft 19 is disposed in a housing 44 having a chamber 46 formed therein, in communication with the chamber 42. The chambers 42 and 46 are of such size and shape as to permit freedom of movement of the respective drive bracket 26 and eccentric 24 during operation of the razor. The shaft 19 projects through openings 47 in walls 48 of the housing 44. The openings 47 are in alignment with the bearings 21 supported in the side portions 23 and are of such dimensions that a clearance is provided between the walls 48 and the shaft 19 which permits free oscillatory movement of the shaft and prevents the entrance of hair clippings to the respective chambers along the shaft 19. It will be seen that with this construction the eccentric 24 and the drive bracket 26 are completely enclosed.

Another aspect of my invention is concerned with an improved construction for securing the comb unit in position at the end of the razor. To this end I provide comb locks on each side of the head which when in the secured position are stressed so as to positively secure the comb unit on spaced shoulders 49 formed on each side of the head 15, and which can be readily removed from engagement with the comb unit when it is desired to remove the comb unit for cleaning or for replacement of the comb and also the cutter.

Each comb lock is in the form of a plate 51 (see Figures 4 and 6) having a tongue 52 on one end shaped to interfit in a slot 53 formed in the lower portion of the comb unit. Each tongue 52 is formed with a cam surface 54 arranged for snap engagement in the slot 53 in the comb unit, as shown in Figure 4. Each plate 51 has a hinge-like connection at its lower end to a spring member 56 which is stressed to pull the plate downwardly and yieldingly hold the tongue 52 engaged in the slot 53. The spring members 56 are formed integral with a plate 40 of spring steel (see Figure 11) disposed between the head 15 and a bearing block 57 of the motor 27, the spring plate 40

being shaped to cover the entire top of the bearing block and having suitable openings for the motor drive and for fastening screws. Each spring member 56 extends the full width of its companion plate 51, thus providing a continuous hinge-like connection and a strong and durable spring action for retaining the comb in position under all service conditions. To disengage the tongue 52 and slot 53 it is only necessary to insert a thumbnail between the upper edge of the plate 51 and the comb assembly and apply a slight outward pressure. The plate 51 may then be swung down to the open position shown in Figure 6. The spring member 56 acts to retain the plate 51 in this open position, exerting a downward pressure against the plate 51, as will be presently described.

Another important feature of my construction is the chambers 58 formed on each side of the shaver 11 for receiving the hair clippings. Herein the chambers 58 are formed between the side walls 43 of the head 15 and the comb locking plates 51. Each of the chambers 58 is in communication with the cutter chamber 41. Preferably the exterior of the housing 44 disposed in the chamber 41 is arcuate shaped (see Figure 4) so that hair clippings falling thereon are deflected into the side chambers 58. Access to the chambers 58 for cleaning purposes is effected by disengaging the tongue 52 from the slot 53 and swinging the plates 51 about its said hinge-like connection. This hinge is formed by bending an outer portion 59 of the spring member 56 in a downwardly curved direction as shown in Figure 4 and bending a lower portion 61 of the plate 51 in an upwardly curved manner to interfit with the curved portion 59 of the spring member 56. It is to be understood that when the tongue 52 is disengaged from the slot 53 as in removing the comb the spring member 56 tends to assume an unstressed position. As a result, the plates 51 are moved bodily downwardly so that the curved edge 61 of the plate engages an edge 62 (see Figure 6) of the casing 11. To gain access to the chambers 58 the end of the plate 51 is swung outwardly to the position as shown in Figure 6. During the movement of the plate 51 to this position the curved edge 61 is rotated in a counter-clockwise direction on the edge 62 of the case to bring its interlocked or hinged end to a passed center position in which the downward pressure of the spring member 56 holds the plate 51 in the open position shown in Figure 6. That is, the end portion 61 in effect goes through an overcenter position and the plate 51 is yieldingly held in such position by the spring member 56. A slight movement of the plate 51 in the direction to return it to the position shown in Figure 4 causes the spring member 56 to go overcenter in the opposite direction and assume an unstressed position. As a result the plate 51 will be swung about its hinge to an upright position with its tongue 52 against the comb unit and ready to be snapped into interlocking engagement therewith.

Another phase of my invention is concerned with constructing the head 15 of the razor in such a manner as to facilitate assembly of the respective parts mounted in and supported thereby. Herein I form the head in two separable parts 63 which when joined together along a common plane passing substantially through the longitudinal axis of the shaft 19 forms the unitary head. Each of the parts 63 is identical and assumes the shape best shown in Figure 9. Each of the parts comprises side members 64 having

recesses 66 which when two parts are secured together form the bearing openings 22 (see Figure 3), an intermediate portion 67 spaced from the side portions 64 and when the parts 63 are assembled form the housing 44, webs 68 and 69 interconnecting the side portions 64 and the intermediate portion 67 and flanges 71 utilized in mounting the head 15 on the motor block 57. A dowel pin 72 on one part 63 shaped to fit in an opening 73 in another part 63 may be utilized to align the respective parts 63. In assembly, the flat face of each part, lying in a common plane, abuts the corresponding face of the other part 63. Any suitable means may be utilized for securing these parts together, such as two screws 74 (see Figure 3) extending through one of side portions 64 into threaded engagement with a corresponding part 64.

Means is provided for controlling the axial movement or end play of the cutter shaft 19. To this end the sleeve bearings 21 (see Figure 3) mounted in the side portions 23 are formed with shoulders 76 shaped to abut against shoulders 77 formed on the shaft 19. The sleeve bearings 21 are of sufficient length so that a portion 78 of the head 15 adjacent the openings 22 receiving the bearings 21 may be deformed to engage the end of the bearing opposite the shoulders 76 and thereby positively position the sleeve bearings 21.

In assembly of the component parts of the head 15 the sleeve bearings 21 are normally placed on opposite ends of the shaft 19 and the shaft with the cutter supports 18 and drive bracket 26 are mounted in one of the parts 63. The mating part 63 of the head 15 is then brought into position so that its edge portions abut the edge portions of the other part and then the screws 74 are threaded into position from each side of the head 15. The completed head is then placed in a machine and the portions 78 of the head 15 adjacent the openings receiving the bearings 21 are deformed as by a spinning process. It is to be understood however that there is sufficient clearance between the shoulders 76 and 77 to permit freedom of angular movement of the shaft 19 and while at the same time preventing axial movement of the shaft.

While any suitable motor 27 may be used to drive the eccentric 24 I prefer to use a motor of the type described in detail in my co-pending application, Serial No. 783,419, filed October 31, 1947. Preferably, the motor comprises a field structure 79 composed of two separable pieces secured together by links 81 at opposite ends thereof and having field coils wound on spools

82 formed by two interlocking portions to form a unitary field structure of a generally elongated rectangular shaped cross-section encircling an armature 83. The latter is supported by a shaft 84 in self-aligning bearings 86 (see Figure 4) and 87 (see Figure 7) supported in bearing blocks 57 and 89 secured in a suitable manner to opposite ends respectively of the field structure 79.

While any suitable means may be utilized for securing the motor 27 to the head 15, I utilize screws 80 projecting through the flanges 71 on each side of the head and threaded into the bearing block 57. The universal motor shown herein is a series motor of the commutating type. Means is provided for effecting a connection between brushes 91 and the motor circuit that facilitates assembly and maintenance of the motor. For this purpose I utilize tubular shaped brush holders 92 (see Figure 7) shaped to hold the brushes 91 and provide a removable cap 93 electrically con-

neeted in the motor circuit and shaped to fit over the end of each tubular member 92 to effect a connection between the brush holders 92 and the motor circuit. As best seen in Figure 7 the motor herein utilizes two brushes 91. The brushes are received in the brush holders 92 herein in the form of tubular sleeves supported by the bearing block 89 so that one end of each sleeve is disposed adjacent a commutator 94 and the other end projects through a wall 96 of a commutator chamber 97 formed in the bearing support 89. The sleeves 92 are disposed on opposite sides of the commutator 94 in a predetermined manner to obtain proper commutation. The outer end of each sleeve 92 is formed with a bead 98. The cap 93 herein is formed with a central portion 99 and depending resilient fingers 101 shaped to interfit with the bead 98 so as to secure the cap 93 to the end of the sleeve 92. A portion 102 of each cap 93 is shaped so that field leads 103 can be secured thereto as by hooking an end of each lead 103 through an opening in the portion 102 and soldering the respective parts together. The pressure of each brush 91 on the commutator 94 is determined by a spring 104 disposed between a shoulder 106 formed on the brush 91 and the cap 93. This construction is advantageous in that the electrical connections and the brushes 91 are readily accessible from the exterior of the motor 27 for maintenance and service purposes. It also permits the use of a relatively long spring 104 between the position 91 and the cap 93 which is desirable since the longer the spring the less variation there will be in brush pressures on the commutator 94 as the brush wears down in use. In some applications such as when the motor is used in the case 28 which is formed by separable parts joined together as described in my prior Patent No. 2,530,302, I utilize a strip of mica insulation 107 between the cap 93 and the case 28. This provides additional protection to the user of the razor against induced voltages in the motor and the like because the case is split at this point.

Frequently, in electric razors the construction of power terminals 108 and a plug (not shown) for connecting the respective terminals to a source of power is such that a positive connection between the respective parts is not always assured. This is aggravated by the fact that in operation, particularly where the power terminals are located at a lower portion of the electric razor the weight of the attachment plug and connected cord tends to pull the plug from engagement with the terminals 108. A construction of the power terminals 108 is shown herein for positively assuring an electrical connection under extreme service conditions. To this end the power terminals are formed as elongated prong members projecting through an insulating panel 109, slidably disposed in spaced opposed grooves 111 formed on opposite sides of a recess 112 receiving the terminals 108 at the extreme outer end of the bearing block 89. As shown in Figure 7 the recess 112 is disposed so that the terminals 108 are accessible from the exterior of the case 28 through an opening 113 formed therein. Field leads 114 are connected to the terminals 108 through eyelets 116 embracing one end of the terminals 108. Herein the eyelet 116 is disposed between an insulating member 117 on one side of the insulating panel 109 and a peened end 118 on each terminal 108. The peened end 118 in effect forms a riveted connection which coacting with an annular shoulder 119 formed on each terminal on the opposite side of the insulating

panel 109 secures the terminals 108 thereto in a rigid relation. The end of each terminal 108 projecting into the recess 112 is formed with an axially extending slot 121 (see Figure 8) that substantially bisects the terminals 108. With this construction each of the bisected parts of the terminal is slightly resilient and when in use with a plug of predetermined design as described in my co-pending application will be stressed so that the outer ends of each bisected terminal are moved toward each other in a stressed condition. Intermediate the ends of the terminals 108 the latter are deformed as by forming an annular bead 122 thereon. Preferably the plug (not shown) is formed with sleeves having an annular recess shaped to receive the annular shoulder 122 formed on the prongs 108.

In some motor applications the axial movement and end play of the shaft 84 must be maintained within extremely close tolerances to insure optimum operation. A construction for minimizing the end play of the shaft 84 when the motor 27 is used for driving the electric razor 11 is shown in Figures 3 and 4. Thus, an abutment 123 is formed on the shaft 84 as by a collar being press fitted on the shaft adjacent an insulating disc 124 disposed adjacent the bearing 86. A washer 125 is disposed between the collar 123 and a sleeve member 127 of the self-aligning bearing 86. A second washer 128 is disposed between the opposite end of the sleeve member 127 and a shoulder formed on an eccentric supporting shaft 131, rigidly mounted at one end on the shaft 84. The washers 126 and 128 are selectively chosen during assembly of the motor 27 so that only washers of a thickness permitting the shaft 84 to freely rotate without appreciable end play are utilized in the assembly.

The eccentric 24 may be secured to the shaft 84 in any suitable manner. Herein by way of illustration the eccentric 24 is mounted on the shaft 131 which is threaded into the end of the shaft 84. Preferably, the eccentric is mounted in an insulated relation with respect to the shaft so that induced voltages in the armature 83 and the shaft 84 are prevented from passing to the comb 12 and the case 28. As shown in Figures 3 and 4 the eccentric 24 is in effect integral with and projects upwardly from a washer 132 mounted on the shaft 131. The inner opening of the washer is preshaped to fit about an insulating washer 133 mounted on the shaft. Insulating washers 134 and 135 are disposed in spaced axial relation on opposite sides of the washers 132 and 133. The respective washers are secured between a shoulder 136 and a washer 137 by peening over an end 140 of the shaft 131 so that it engages the washer 137 and in effect rivets the respective washers together.

Suitable provision is made for oiling the motor bearings 86 and 87 from the exterior of the case 28 in which the motor is supported. For this purpose passageways 138 formed in bosses 139 on the interior of the case 28 are positioned to form a continuation of passageways 141 in communication with the bearings 86 and 87 respectively and extending through bearing blocks 88 and 89 respectively. To facilitate alinement of the passageways each boss 139 is shaped to interfit in a recess 142 formed in one end of the passageways 141 in the respective bearing blocks. The recesses are somewhat larger than the bosses so as to allow for tolerances in manufacture. To prevent leakage of oil from the passageways to the motor a gasket 143 is disposed between a

shoulder 144 formed on the brush and each respective bearing block.

The case 28 shown herein is formed in two parts as described in detail in my prior Patent No. 2,530,302 referred to above. Each of the parts is secured to the motor assembly in a rigid manner as by screws 146 (see Figure 3) securing one end of the case to the head 15, screws 147 (see Figure 7) securing the opposite end of one of the parts to the motor and screws 148 securing the opposite end of the other part to the motor. Preferably a shield 149 overlies the screws 146 and joints between the parts so that the case has a neat and attractive appearance. Each shield is secured to the case 28 by a bracket 151 (see Figure 3) interfitting with a clamp 152 secured to the case 28 and by deforming an end 153 of the shield 149 to engage a shoulder 154 (see Figure 7) formed adjacent the opening 113 at the power terminal end of the razor.

While I have shown one embodiment of my invention it will be understood that I do not wish to be limited thereto since many modifications may be made and I therefore contemplate by the claims to cover such modifications as fall within the true spirit and scope of my invention.

I claim:

1. A shaver comprising a head, an arcuate comb removably mounted on the head, a cutter, means for oscillating the cutter in coaction with the inner side of the comb including a rock-shaft mounted in the head, the head shaped to provide hair receiving compartments at opposite sides thereof communicating with the comb interior and extending lengthwise of the head, each such compartment communicating with the comb interior, and a plate closing the outer side of each such compartment, each plate having a hinge-like mounting on the shaver at its lower end and adapted to be swung outwardly on such mounting to expose the full length of said compartment for cleaning.

2. A shaver having, in combination, a head, an arcuate comb removably mounted on the head, the head shaped to provide hair receiving compartments at opposite sides thereof communicating with the comb interior and extending lengthwise of the head away from the comb, and a plate closing the outer side of each such compartment, each plate having a hinge-like mounting on the shaver at its end remote from the comb and adapted to be swung outwardly on such mounting to expose said compartment between such mounting and the comb for cleaning, and means coacting between the opposite end of each plate and the comb for the detachable engagement with the comb to hold the comb in position.

3. In a shaver in combination with a shaving head having a removable comb and a hair receiving compartment communicating with the comb interior, a closure member for normally closing said compartment and adapted to be moved to an open position to provide access to the compartment for cleaning, means coacting between said closure member and the comb for snap

engagement therebetween upon movement of said member to the closed position, and means coacting between the head and the opposite end of said member providing a hinge-like connection and including a spring member stressed to urge said member in a direction to maintain said snap engagement and also in a direction to hold said member in the open position.

4. In a shaver, a head, a comb unit supported by said head and having slots formed thereon at opposite ends, resilient members at the base of said head and having curved edge portions, side plates each having a tongue to interfit with the slots on said comb and having a second curved edge shaped to interfit with one of the curved edge portions on said resilient member, said resilient members being shaped so that with the tongues interfitting with the respective slots they are stressed to positively secure the comb in position on the head.

5. In a shaver, a head, a comb unit supported at one end of said head and having apertures formed on opposite sides thereof, spring members mounted at the opposite end of said head having outer curved edges, side plates mounted on opposite sides of said head, said plates being formed at one end with a projection shaped to interfit in said apertures for securing the plates and comb assembly in position and at their opposite end with a second curved edge shaped to interfit with said curved edge on the spring members so as to form a hinge, said plates being spaced from said head to form hair receiving chambers on opposite sides of said head, said side plates being shaped to swing about said hinge for access to said chambers.

6. A shaver comprising a head, an arcuate comb removably mounted on said head, said head being shaped to define a hair receiving compartment below said comb and within a space which would be defined by an extension of said comb, said hair receiving compartment communicating with the comb interior and extending lengthwise of said comb and also communicating with the exterior through an opening defined immediately beneath the lowermost portion of said comb, and a plate closing said opening and, hence, said hair receiving compartment, said plate having a hinge-like mounting on the shaver at its end remote from said comb and adapted to be swung outwardly on such mounting to expose said hair receiving compartment for cleaning.

IVAR JEPSON.
